(57) **CLAIM**

The ornamental design for a wig cap, as shown and described.

DESCRIPTION

FIG. 1 is a front elevation view of a wig cap showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is another perspective view thereof.

Areas within the broken line boundaries in FIGS. 1, 3, 4, 6, 7, and 8 represent portions of the wig cap that form no part of the claimed design.
